UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

PULSATION-PREVENTING MECHANISM.

1,280,812.

Specification of Letters Patent.

Patented Oct. 8, 1918.

Application filed February 2, 1917. Serial No. 146,128.

To all whom it may concern:

Be it known that I, SANFORD A. Moss, a citizen of the United States, residing at Lynn, in the county of Essex, State of Massachusetts, have invented certain new and useful Improvements in Pulsation-Preventing Mechanisms, of which the following is a specification.

The present invention relates to pulsation preventing means for centrifugal compressors, such as air compressors. The object of the invention is to provide an improved arrangement for preventing pulsations in compressors, which arrangement is automatic in operation, simple to build, and easy to install, either on new machines or those already in use. The invention, while it is not necessarily limited thereto, is particularly intended for use in connection with compressors equipped with constant volume governors.

For a consideration of what I believe to be novel and my invention, attention is directed to the accompanying specification and the claims appended thereto.

In the accompanying drawing, Figure 1 shows a turbo-compressor unit equipped with a constant volume governor and with my improved pulsation preventing mechanism; Fig. 2 is a detached side elevation partly in section of the pulsation preventing mechanism, and Fig. 3 is a top plan view thereof.

Referring to the drawing, 5 indicates a centrifugal compressor having an inlet conduit 6 and a discharge conduit 7. It is shown as being driven by a steam turbine, a portion of which is indicated at 8. 9 indicates a valve mechanism which controls the admission of elastic fluid to the turbine, and 10 a fluid actuated motor for operating it. The turbine driven compressor set is provided with a usual form of constant volume governor comprising a pivoted beam 11 connected at one end by a rod 12 to a float 13 in the inlet conduit 6. The other end of beam 11 is connected through links 14 and 15 to the fluid motor 10. 16 indicates the constant volume governor weight and 17 the hand wheel for adjusting it along the scale on beam 11. The fluid motor 10 is also suitably connected to a speed governor 18 as shown. The operation of a constant volume governing mechanism as just described is well known. The weight 16

is set on the scale for the desired volume of flow and the float 13 acts on the beam 11 to tilt it so as to cause the fluid motor 10 to open and close the valve mechanism 9 to maintain the turbine 8 at the speed required to supply the volume of air desired. If the volume of air flowing tends to decrease then the float 13 lowers a little thus tilting the beam 11 and opening the valve mechanism 9 to admit more elastic fluid to the turbine 65 so as to increase the speed and thus cause the compressor to take more air. On the other hand, if the volume tends to increase then the opposite action takes place. The speed governor 18 is normally inactive, the 70 turbine being wholly under the control of the constant volume governor, and only comes into play to take control in case of excess speed. It is somewhat of the nature of an emergency governor. The constant 75 volume governing mechanism as just described is well known and forms no part of the present invention, except that it may enter into the general combination.

19 is a by-pass conduit connected with the 80 discharge side of the compressor and used for wasting air in order to prevent the occurrence of pulsations, this method of preventing pulsations being one which is now well known. In the present instance it is 85 shown as connecting the discharge end of the compressor to the inlet end beyond the constant volume governor, this arrangement being a preferable one as it assures that all the air which is measured by the constant 90 volume governor is utilized. Arranged in the by-pass conduit 19 is a swinging check valve 20 carried by an arm 21 which is pivoted on a rod 22 journaled in the valve casing 23. This valve opens toward the inlet 95 end of the compressor and is adapted to be opened by the pressure existing upon the discharge side of the compressor. 24 indicates a stop for limiting the opening movement of the valve. The rod 22 projects well 100 beyond the valve casing 23 at one side and has fixed thereon a frame 25 having a scale marked thereon and carrying an endless screw 26 adapted to be turned by the hand wheel 27. Sliding on the frame 25 is a 105 weight 28 having a threaded portion which engages the screw 26. By turning the hand wheel 27 the weight may be adjusted along the frame 25 as is obvious. The weight 28 acts to bias the valve 20 to closed position. 110

The point at which pulsations occur in a centrifugal compressor depends upon the volume and pressure. In fact, it is now known to depend upon the volume divided by the square root of the pressure, which may be termed the load coefficient of the machine. As long as the load coefficient keeps above a certain value pulsations will not occur, but when it reaches or falls below this value they may occur. The value of the load coefficient at which pulsations commence may be termed the critical value. This critical value differs for different machines and can only be determined by experiment. With a machine equipped with a constant volume governor the volume delivered by the machine remains constant. With such a machine, therefore, it will be evident that the critical value is directly a function of the square root of the pressure. In other words, for every volume for which the constant volume governing mechanism may be set there is a pressure at or above which pulsations will occur.

In the operation of my improved apparatus the constant volume governor having been set for the desired volume of flow, the weight 28 is adjusted along the scale on the frame 25 to the point corresponding to the setting of the constant volume governor. If now the pressure on the delivery side of the compressor increases to a point where it brings the load coefficient down to a value where pulsations are about to occur, then said pressure will open the valve 20 more or less against its biasing force and so waste air from the delivery to the inlet side of the compressor.

What I claim as new and desire to secure by Letters Patent of the United States, is:—

1. The combination with a centrifugal compressor having a constant volume governor which may be set for the desired volume, of a by-pass conduit connected with the discharge side of a compressor, a valve in the conduit adapted to be acted on directly by the pressure in the conduit, said pressure tending to open the valve, means connected with the valve which biases it toward closed

position, and adjustable means associated with said biasing means for increasing or decreasing the force of said biasing means whereby the biasing means may be set in accordance with the setting for the constant volume governor.

2. The combination with a centrifugal compressor having a constant volume governor, of a by-pass conduit connecting the discharge side of the compressor to the inlet side, a valve in the conduit adapted to be acted on directly by the pressure in the conduit, said pressure tending to open the valve, a frame having a scale thereon connected with the valve, and a weight on the frame which acts to bias the valve toward closed position, said weight being adjustable on the scale so that it may be set in accordance with the setting of the constant volume governor.

3. The combination with a centrifugal compressor having a constant volume governor, of a by-pass conduit connected with the discharge side of the compressor, a swinging check valve in the conduit adapted to be acted on directly by the pressure in the conduit, said pressure tending to open the valve, and means connected with the valve which biases it toward closed position, said means being adjustable so its biasing force may be regulated in accordance with the setting of the constant volume governor.

4. The combination with a centrifugal compressor having a constant volume governor, of a by-pass conduit connecting the discharge side of the compressor to the inlet side, a swinging check valve in the conduit adapted to be acted on directly by the pressure in the conduit, said pressure tending to open the valve, a frame having a scale thereon connected with the valve, and a weight on the frame which acts to bias the valve toward closed position, said weight being adjustable on the scale so that it may be set in accordance with the setting of the constant volume governor.

In witness whereof, I have hereunto set my hand this 31st day of Jan., 1917.

SANFORD A. MOSS.
